(57) CLAIM

The ornamental design for pockets, as shown and described.

DESCRIPTION

FIG. 1 is a front view of pockets showing my new design; FIG. 2 is a front perspective view thereof;

FIG. 3 is another front perspective view thereof;

FIG. 4 is a front elevational view thereof; and,

FIG. 5 is a rear elevational view thereof.

The broken line showing of a shirt in FIG. 1 is included for the purpose of illustrating environmental structure and forms no part of the claimed design.

The broken lines shown throughout the views, on the surface of the pockets, represent stitching.
